PERMUTATION SYSTEM OF SERIES
CIRCUIT CONTROLTheodore R. Hennigar, Chester Basin, and Harry
B. MacKay, Mahone Bay, Nova Scotia, Canada

Application October 20, 1948, Serial No. 55,564

3 Claims. (Cl. 200—43)

1

This invention relates to a permutation system of series circuit control, and the object of the invention is to provide a permutation system for any type of series circuit to make it impossible for an unauthorized person to close said circuit.

The invention broadly consists of a system embracing at least two contact points in a series circuit of any type; a like number of normally-closed self-closing cutout switches in said circuit; a key having at least two current-conducting extensions adapted to contact said points simultaneously to close said circuit therethrough, and normally dormant means intermediate said contact points and said switches adapted to be actuated to open one or both of said switches when a key, having one or more extensions of greater reach than the extensions of said first-mentioned key, is used in an attempt to close said circuit.

In its preferred embodiment, the invention consists of a system embodying a plurality of staggered contact points in a series circuit of any type, each positioned in a channel longitudinally formed in a suitable panel; a like number of normally-closed self-closing cut-out switches in said panel each reached through a channel in said circuit; a portable key having a like number of parallel key-rods of different extension or reach coupled together in pairs and adapted to be passed into said channels to contact said contact points simultaneously to close said circuit therethrough, and a normally dormant rod in each of said channels, between said switches and said contact points, adapted to be moved to open any of said switches when moved by a key having an extension of greater reach than said key-rods when an attempt is made to close said circuit.

Fig. 1 is a schematic view showing, in section, an embodiment of the system for the control of a door latch.

Fig. 2 is a plan of the inner end of the key.

In the drawings, like characters of reference refer to the same parts.

In its preferred form the invention comprises a plurality of key-rods 2, wired together in pairs in spaced relationship, as at 3. These rods essentially reach or extend varying distances beyond a portable support 4, therefore, which, together with said rods, is hereinafter referred to as the key. The said support 4, may be made of any suitable non-conducting material so that the key rods 2 may be insulated from each other. If said support is made of current-conducting material the key rods 2 must be suitably insulated therefrom. A panel 5 preferably made of any suitable insulating material, is provided with as

2

many parallel channels 6 as there are key-rods 2. These channels are spaced a distance apart equal to the distance separating said key-rods, and are to open at one end through the same side of the panel. Contact points 7 are located with respect to said channels 6, so that when the key-rods 2 are passed thereto they will make contact with said contact points. The location of said contact points in said channels and the individual length or reach of the key-rods 2, is such that said key-rods simultaneously make contact therewith when they have been fully inserted into said channels.

Slideable in said channels 6 are normally-dormant non-current-conducting rods 8, normally out of contact with the key-rods 2. Each channel opens into a pocket 9 in said panel, and in each pocket are two terminals, 10 and 11. Fastened to each terminal 11, is a spring-key 12, which normally presses against its associated terminal 10. These spring-keys 12, and terminals 10 and 11, are hereinafter referred to as cut-out switches.

Bearing in mind that at least two key-rods must simultaneously contact two contact points 7 to close the circuit, if attempt should be made to use a key in which any key-rod reaches up into a channel 6 far enough to contact the associated rod 8 thereof, it will move this rod to move the key 12 out of contact with its terminal 10, thus opening the circuit before the contact points 7 can be simultaneously contacted by all of its key-rods. Thus it will be seen that keys can be made usable with certainty only in a given panel, and hence a very wide range of keys and panels can be made. As before mentioned, the drawing shows the system adapted to be used to control the latch or bolt of a door. When the current is closed solenoid 13 is magnetized and withdraws the bolt or latch 14 from the outer dotted position into the inner dotted position, thus unlocking the door 15. When the key is removed from the panel, the circuit is opened, and the solenoid demagnetized, thus permitting the spring 16 to return the bolt or latch 14 in position to lock the door when it is shut.

The current enters through the feed-wire *a* to the terminal 11, through the key 12 to the terminal 10, through the wire *b*, through similar terminals 50 and keys into the wire *c*, and on through like wires and terminals and keys clearly shown to the contact point 7 at the right-hand side of the panel and continues on through the key-rods 2 and wires 3 to the contact points 7 wired together in the middle of said channel and finally out from

the contact point 7 at the left-hand side of the panel, through the wire d, and by way of the solenoid 13 into the return wire e, thus completing the circuit.

Even if only two contact points 7 are used, the distance of same within the channels 6 may be the same, and two key-rods of equal reach used therewith may contact said points simultaneously. A very wide range of permutations can be obtained with the elements just mentioned, in combination with rods 8, but obviously a very much wider range of permutations can be obtained where a greater number of pairs of key-rods 2 and contact points 7 are used.

The principle of the invention may be embodied in many different forms without going outside the scope of the specification and claims other than that herein described and illustrated, although for the purpose of explaining the invention it is shown and described as controlling a series circuit including a lock for a door.

We claim:

1. A permutation system of series circuit control comprising a circuit; at least two contact points in said circuit; a key having at least two current-conducting extensions adapted to contact said contact points simultaneously to close said circuit; two normally-closed cut-out switches in said circuit, and normally dormant means intermediate said contact points and said switches adapted to be actuated to open one or both of said cut-out switches when another key, having one or more extension of greater reach than the extensions of said first-mentioned key is used in an attempt to close said circuit.

2. A permutation system of series circuit control comprising a circuit; at least two contact points in staggered relations in said circuit; a key having at least two current-conducting extensions of different reaches adapted to contact said contact points simultaneously to close said circuit;

two normally-closed cut-out switches in said circuit, and normally dormant means intermediate said contact points and said switches adapted to be actuated to open one or both of said cut-out switches when another key, having one or more extensions of greater reach than the extensions of said first-mentioned key is used in an attempt to close said circuit.

3. In a permutation system circuit control a panel, made of suitable insulating material, provided with a plurality of parallel channels each opening at one end through the same side of the panel; a plurality of normally-closed cut-out switches housed in said panel and each accessible from a channel; a contact point in each channel in staggered position in relation to its fellows accessible from the open end thereof; a common series circuit for said switches and contact points; a portable key having a number of key-rods of different extensions or reaches coupled together and adapted to be passed into all of said channels to contact said contact points simultaneously to close said circuit therethrough, and a normally-dormant non-current-conducting rod longitudinally movable in each of said channels and normally out of contact each with its associated switch and adapted to be actuated to open one or both of said plurality of cut-out switches when a key, having one or more extensions of greater reach than the extensions of said first-mentioned key is used in an attempt to close said circuit.
